LUIGI ROBIMARGA, OF MILAN, ITALY.

DEVICE INSURING IN A CONTINUOUS AND AUTOMATIC MANNER THE SYNCHRONISM BETWEEN A GRAMOPHONE AND A CINEMATOGRAPHIC PROJECTION MACHINE.

Application filed July 23, 1924, Serial No. 727,735, and in Italy July 26, 1923.

This invention concerns a device insuring the synchronism in the movement of a gramophone to be driven together with a cinematographic projection machine for the purpose of giving the phonetical reproduction accompanied by the optical reproduction of a moving picture. Many such devices have already been suggested in order to solve this problem, but, as a rule, they only allow the operator to compensate a phase discordance in the machines when it has already been verified and the operator himself has perceived it.

The object of the invention instead is to prevent any noticeable discordance from arising and to eliminate the slight discordances which may occur from time to time, on account of perturbing causes.

For this purpose on the transmission of the movement to one of the two machines, preferably of the projection machine, a change speed gear is provided allowing two speeds almost alike, the lower of said speeds being less than the lowest speed allowable by the motor to the gramophone machine and the higher being greater than the highest speed allowed by the motor to the gramophone.

Said device with double gear ratio is periodically controlled in its working, at short intervals of time, at the end of each one of them an automatic switch enters into action leaving unchanged the connection if both machines are in phase concordance and causes it instead to pass from the higher to the lower ratio or from the lower to the higher ratio if the cinematographic machine is lagging behind or running ahead.

In this way the speed is continuously adjusted and it is not possible for the phase discordance to reach appreciable values.

In the drawing which serves to illustrate the synchronism regulator according to this invention:

Fig. 1 shows a top view of the complete apparatus adapted to be connected with the projection machine;

Fig. 2 is a vertical section of the same according to line X X of Fig. 1.

Fig. 3 is a detail of Fig. 2.

Fig. 4 is a view of the electrical connections of the apparatus with a two disc gramophonical machine.

In the several figures of the drawing the same reference numerals are used to indicate corresponding parts.

As it may be seen from the drawing the apparatus includes a general foundation plate 1 upon which are suitable supports 2, 3. In the supports 2 is mounted a shaft 4 to which, by means of a pulley 5 on which runs a belt 6 is imparted the movement by the electrical motor which drives the whole plant, and in the supports 3 is mounted a shaft 7 which sets into motion the projection machine not shown in the drawing, and bears a little fly-wheel 8.

Both shafts 4 and 7 are connected together by means of the double speed gear built in the following manner.

Upon supports 9 is rotatably mounted a shaft 10 upon which are keyed a toothed wheel 11 and a pinion 12. The toothed wheel meshes with a pinion 13 borne by the shaft 7 aforesaid: the pinion 12 meshes with a toothed wheel 14 keyed upon a shaft 15 carried by a support 16 and connected with a hand 17 running upon a dial 18, which will be described hereinafter.

Upon the shaft 10 are besides mounted loosely the two toothed wheels 19 and 20 respectively gearing with the pinions 21 and 22 of different diameters both keyed on the shaft 4.

With the wheel 19 is connected and made integral with it, a ratchet wheel 23 on whose teeth rests, pressed by a spring 24, a lever 25 revolving around a pivot 26 fastened upon a disc 27 also loose on the shaft 10; in Fig. 1 the lever 25 has been omitted in order to better show the underlying ratchet wheel 23. The lever 25 rests upon the crown of the wheel 23 with a tooth 28 forming a ratchet coupling for the wheel 19, and the disc 27, such that the wheel 19, by means of the wheel 23 which is integral with it, carries in its movement the disc 27 when the wheel turns in the direction shown by the arrow —z—. The disc 27, on the face opposite to that on which is mounted the lever 25, bears a tooth 29 which meets with a similar tooth 30 projecting from that face of the wheel 11 which is turned towards disc 27. When both teeth 29, 30 are in contact, and the wheel 19 turns in the direction of the arrow —z—, the wheel 11 is carried in the movement of wheel 19 and turns together with it.

The same wheel 11, on its opposite face, turned towards the wheel 20, bears a crown gear 31 on which ride two teeth 32 projecting from the face of the wheel 20 each of said

teeth passing through the wheel 20 and being connected at 33' with a spring 33 which is fastened to the left side of the wheel 20 and tends to keep the teeth 32 pressed against the 5 said crown. The shape of the crown gear 31 is such that when the wheels 11 and 20 turn both in the same direction as shown by arrow —*z*—, and the wheel 11 moves at a higher speed than the wheel 20, it lags behind while 10 the teeth 32 ride upon the crown 31. If instead the connection between the wheel 19 and the disc 27 is severed and the tooth 29 does not carry along the tooth 30 then the teeth 32 cause the wheel 11 to advance at the same 15 speed of the wheel 20.

The connection between the wheel 19 and the disc 27 may be severed in the following manner.

A spindle 34 carried by supports 35 bears 20 on one of its ends a tooth 36 and on the other end the armature 37 of an electro-magnet 38, and by a spring 39 which is coiled around it is continually pushed to take the position shown in the drawing, wherein the tooth 36 is 25 placed in the way of the lever 25, in such manner that the latter turning together with the disc 27 in the direction of the arrow —*z*— of Fig. 3, strikes its end upon the tooth 36, which disconnects it from the wheel 23 thus breaking 30 the connection between the wheels 19 and 11. The stroke of the spindle 34 is limited by a pin 40 which strikes against one of the supports 35. When the electro-magnet is energized, it attracts the armature 37, drawing 35 back the spindle 34, so that the tooth 36 meets no longer the end of the lever 25 which therefore can proceed further remaining coupled with the wheel 23.

The energization of the magnet 38 takes 40 place at each turn of the wheel 19, correspondingly to the passage, in the projection machine, of a certain number of pictures conveniently determined, i. e., 25 or 30 pictures. The switch which breaks off the circuit is controlled by the gramophonical machine, every 45 time it has turned by an angle which corresponds to the recording of the sounds within the time of the passage of the 25 or 30 pictures.

50 Assumed that the gramophonical machine has two disc carriers working alternately, the arrangement of the circuit may be that shown by Fig. 4.

On each of the two shafts 41', 41'' of both 55 gramophones is connected a disc 42', 42'', bearing a contact 43', 43'' electrically connected by means of a wire 44 to one of the poles of a battery 45, or any other source of electricity, the other pole of which is electrically connected by means of wire 46 to one of the terminals of the electro-magnet 38. The other terminal of the electro-magnet through a wire 47 is connected to two stationary contacts 48', 48'' which are met by the 60 moving contacts 43', 43'' at every turn of the

disks bearing them. The two disks do not however move at the same time as the two gramophones are connected together with the driving device so that when one is rotating the other remains stationary, and conversely. 70 Besides matters are arranged in such manner that at the end of the movement of one of the gramophones, for instance that which is connected with the disc 42', the movable contact 43' of 42' will be on the moment of reaching the stationary contact 48' in the direction of the movement shown by the arrow —*w*— as shown in the figure. Thus when the disc 42' begins again movement, the contact 43' meets immediately the contact 48'. Each turn of 80 one of the disks 42', 42'', corresponds always to the same number of pictures on the film.

The number of pictures already projected is at every moment marked by the hand 17 on the graduation not shown of the disc 18 for, as it results from the foregoing description, the shaft 10 on which are mounted the pinion 12 and the wheel 11 moves together and in the prescribed speed ratio on one hand the shaft 15 of the hand 17 by means of the wheel 14, 90 and on the other the shaft 7 of the projecting machine through the pinion 13. All the above premised it is now easy to understand the working of the whole device.

Assumed that the gramophone connected with disc 42'' be in operation, that is to say that the electrical connections are in the conditions shown in Fig. 4, so that the disc 42' is at rest, and the circuit of the electromagnet 38 be cut off, both in 48' and 48'', in these conditions the mechanical connections are also in the condition shown by Fig. 1; that is the lever 25 resting with its tooth upon the ratchet 23 turning in the direction of arrow —*z*—.

The pinions 21 and 22 are continually in 105 contact with the loose wheels 19, 20, but as the pinion 21 has a larger diameter than the pinion 22, thus the wheel 19 turns at a higher speed than the wheel 20. Consequently, as the ratchet wheel 23 by means of the lever 25 carries with it the disc 27 and the latter with its tooth 29 carries along with it the wheel 11, the wheel 11 moves at a higher speed than the wheel 20 which lags behind, which it is allowed to do by the riding of the yielding teeth 32 upon the crown 31. In this period the transmission of the movement from the pulley 5 connected to the motor, to the shaft 7 connected to the projection machine, happens through the couple of gears 21, 19, while the couple 22, 20 remains inoperative.

When, advancing in its rotation the moving contact 43'' arrives against the stationary contact 48'', which happens when the gramophone disc has rotated enough for its point to have covered the arc corresponding to the number of pictures assigned, the electro-magnet 38 is energized and withdraws the spindle with the tooth 36 and in this 115 120 125 130

moment three cases might arise as regards the movement of the film, that is that it be in synchronism, in advance or lagging behind in respect of the gramophone.

5 If both machines are in synchronism the withdrawal of the tooth 36 occurs just when it reaches the position to meet the end of the lever 25 and therefore the latter passes on freely keeping the same connection between wheel 19 and wheel 11 and the speed of the projecting machine remains unchanged.

As soon as lever 25 has proceeded further, the contact 43" — 48" is broken off, the electro-magnet becomes inoperative and the electrical and mechanical connections remain in their former state during another rotation of the disc 42".

If the film anticipates, that means that 20 the shaft 7, and therefore the wheel 19 which transmits the movement to it, rotates faster than the disc 42" and therefore the end of lever 25 will meet the tooth 36 a short time before the latter has been withdrawn. During

25 that short time, that is to say until the tooth will become withdrawn the lever becomes withdrawn, thus releasing the connection with the disc 27 which stops and does not drive any longer the wheel 11 with the tooth

30 29. But in such conditions the wheel 11 is brought forward by the teeth 32 at the lower speed of the gear ratio, therefore the film totally or partially loses the lead it had in respect to the gramophone. Then the tooth

35 36 will be drawn back, thereby being reinstated the condition between the wheels 19 — 11, but the speed of the film will not increase instantly once more. The increase of the speed of the film will take place only when 40 the tooth 29 reaches again the tooth 30, which in the meanwhile is progressing with the lower speed.

The third of the three cases mentioned above, that is, the case of the film lagging behind, can never occur, because the arrangement is such that the film always anticipates in respect to the gramophone so that the lever 25 meets the tooth 36 at every rotation of the wheel 19.

50 In practice the duration of one turn and the difference for the two speeds due to the pinions 21, 22, are chosen in such manner that the equalization of the difference of phase when the latter should arise, is effectuated in only one turn, that is in a time which is practically less than one second.

Inasmuch as the pinion 12 is, like the wheel 11, keyed upon the shaft 10, thus whatever be the transmission ratio, the hand 17 always 60 moves synchronically with the film and shows the numbers of the pictures passed. The disc of the gramophone is connected with an indicator, not shown, which gives the number of the corresponding picture in the film; in this 65 way any lack of synchronism between the

two machines may be easily noticed by the operator.

I claim:

1. In a synchronizing device for a gramophone and a projecting machine, both driven by a single motor, a two ratio speed gear interposed in the transmission and adapted to drive the projecting machine, said ratio speed gear comprising a motor driven shaft, a shaft interposed between the former and the shaft of the projecting machine, a toothed wheel secured on said interposed shaft, a pinion on the shaft of the projecting machine and with which the toothed wheel meshes, two gear wheels loosely mounted on the said interposed shaft, two pinions of different diameters on the motor driven shaft and with which the said loose wheels mesh, a yielding means for connecting one loose wheel with the toothed wheel, said yielding means being between the lower speed wheel and the said toothed wheel, a ratchet device for connecting the other loose wheel with the toothed wheel, and means capable of temporarily releasing the ratchet connection upon a lack of synchronism between the two machines.

2. In a synchronizing device for a gramophone and a projecting machine according to claim 1, the yielding connection between the lower speeded wheel of the two ratio speed gear, consisting of a crown wheel on the toothed wheel and two teeth each secured to a spring plate on the said speed wheel and passing through the same, said teeth being adapted to operatively engage the crown wheel or to ride upon the same according to which of the speed gear wheels the toothed wheel is under the action thereof.

3. In a synchronizing device for a gramophone and a projecting machine according to claim 1, the ratchet device between the toothed wheel and the higher speeded wheel, consisting of ratchet wheel integral with said speed wheel, a loose disc on the shaft of the said wheel between it and the toothed wheel and provided on one side with a tooth, the toothed wheel being provided with a tooth with which the tooth of the disc engages, and a pivoted and spring pressed lever on the other side of the disc and provided with a tooth engaging the ratchet wheel.

4. In a synchronizing device for a gramophone and a projecting machine, a motor driven shaft, provided with pinions of different diameter, a projecting machine shaft, a shaft interposed between said shafts, a high and low speed wheel loosely mounted on said interposed shaft and meshing with the pinions of the motor driven shaft, a toothed wheel on said shaft and geared with the projecting machine shaft, a yielding connection between the low speed wheel and the toothed wheel, a ratchet wheel carried by the other speed wheel, a loose disc on the said shaft between the said speed wheel and the

toothed wheel, a spring lever on the said loose disc and provided with a tooth engaging the ratchet wheel, a spring tooth arranged to project into the path of the spring lever to meet and lift it to disengage the lever from the ratchet wheel at every rotation of said loose disc; a gramophone shaft driven at a speed intermediate that of the high and low speed wheels, a disc mounted on the shaft 10 of the gramophone, and means capable of momentarily withdrawing the above named spring tooth from said path at every rotation of the gramophone disc.

5. In a synchronizing device for a gramophone and a projecting machine both driven by a single motor, a motor driven shaft having pinions of different diameters thereon, a high speed gear wheel, a low speed gear wheel, both loosely mounted on a shaft 15 interposed between said motor driven shaft and the projecting machine shaft, said gear wheels meshing with the pinions, a toothed wheel, geared with the shaft of the projecting machine, a yielding connection between the low speed wheel and the toothed wheel, a ratchet connection between the other speed 20 wheel and the toothed wheel and including a

pivoted lever, a disc carrying said lever, a tooth in the path of the lever for lifting it at every rotation of the disc to break the ratchet connection, a disc on the shaft of the gramophone, driven at a speed intermediate that of the high and low speed wheels, and means for withdrawing the tooth at every complete rotation of the gramophone disc, whereby the lever does not meet the said tooth when the projecting machine is rotating at the same speed as the gramophone or is lagging behind, but meets it when the projecting machine is running faster than the 25 gramophone.

6. In a synchronizing device according to claim 5, a spring construction for holding said tooth normally in the path of the lever, an electro-magnet comprising said withdrawing means for operating the tooth, an electric circuit, a stationary contact and a disc on the shaft of the gramophone and carrying a contact adapted to meet the stationary contact at every complete rotation of said disc to close 30 the circuit and withdraw the said tooth.

In testimony whereof I have affixed my signature this 2nd day of July, 1924.

LUIGI ROBIMARGA.
